UNITED STATES PATENT OFFICE.

JAMES T. HAMBAY, OF NEW YORK, N. Y.

ELECTRIC BLOCK SYSTEM FOR RAILWAY-TRAINS.

SPECIFICATION forming part of Letters Patent No. 707,226, dated August 19, 1902.

Application filed March 15, 1902. Serial No. 98,405. (No model.)

To all whom it may concern:

Be it known that I, JAMES T. HAMBAY, of the city, county, and State of New York, have invented a new and useful Electrical Block System for Railway-Trains, of which the following is a specification.

The system in which my invention resides is adapted more particularly for use in tunnels and other localities where the usual block-signals alongside of the track are liable to be so obscured by smoke, steam, and the like as to escape the notice of the locomotive-engineer of the passing train.

The object is to reproduce on the locomotive and in convenient proximity to the engineer the same signal conditions, whether "danger," "caution," or "safety," as may be displayed by the ordinary track-signals; or, in other words, the object is to put the semaphore-signal in the locomotive-cab and directly under the eye of the engineer, the signal thus located being, however, just as much under the control of the tower-man or operator who has charge of the block as are the usual signals alongside of the track. I thus, in effect, transfer the semaphore from the track to the locomotive-cab, and I provide means whereby the operator in charge of the block can operate it there just as though it were on the roadway. This I believe to be new with me beyond its special embodiment hereinafter set forth.

In the system which I have devised there is provided for each block a normally open electric signal-circuit completed through the contacts on the locomotive whenever and so long as the latter is on the block, and including electric signal appliances—such, for instance, as white, green, and red incandescent lamps—located on the locomotive at some point in convenient proximity to the engineer. This signal-circuit has branch connections, one branch for each signal—"safety," "caution," or "danger," as the case may be—and means are provided for completing the circuit through either one of these branches to the exclusion of the other or others, said means being controlled by the tower-man or the operator in charge of the block in such manner that by the simple movement of a lever he can at will excite either one of the signals on the locomotive to the exclusion of

the other or others and can also at will change from one to the other so long as the locomotive is on the block and whether the latter is in movement or not. I prefer also to connect these controlling means with the mechanism for operating the ordinary track-signals, so that the same movement of the lever which sets these track-signals to "safety," "caution," or "danger," as the case may be, will put the signal-circuit connections in condition to complete that circuit through the corresponding signal on the locomotive.

To enable others skilled in the art to make and use my invention, I will now proceed to describe more in detail the manner in which the same is or may be carried into effect by reference to the accompanying drawings, in which—

Figure 1 is a plan of a railway-block embodying my invention. Fig. 2 is a perspective view of a portion of the same. Fig. 3 is a side elevation, on enlarged scale, of a portion of the same. Fig. 4 is an end view of the same, showing the locomotive on the track and also the tower containing the appliances for controlling the signal system pertaining to the block. Fig. 5 is a diagram illustrative of the circuit connections of the system.

Inasmuch as the system is one adapted more particularly for use in tunnels, I have shown the electrical connections between the outside system and the locomotive as overhead connections, consisting in this instance of overhead wires extending lengthwise of the block and trolleys T on the top of the locomotive to make or maintain spring or yielding contact with said wires, as customary in the trolley system. The block has, as usual, the customary track-signals of the semaphore or other suitable kind, the main one, X, the caution or green signal, the far one, Y, the danger or red signal, both of them adapted to be operated from the cabin or tower Z by suitable appliances, typified in Figs. 1 and 2 by the rod x and lever x' for the caution-signal and the rod y and lever y' for the danger-signal. The two levers x' y' should be provided with the customary interlocking appliances whereby the lever x' must be thrown to set the signal X at "caution" before the lever y' can be thrown to set its signal Y at "danger," and vice versa on the return of said le-

vers from "danger" and "caution," respectively, to "safety."

In the locomotive-cab, as seen in Fig. 4, are three electric incandescent lamps G W R 5 adapted when excited to show a green, white, and red light, respectively, and so located as to be readily seen by the engineer. The electrical connections or system of wiring between these lamps and the trolleys T will be 10 hereinafter described in connection with the diagram of circuit connections in Fig. 5. The electric signaling system of the block is divided in this instance into two subsections following the two subsections (caution and danger sections) into which the block is divided by the arrangement and location of the track-signals X and Y. The three overhead wires $g' g^2 g^3$ extend from the entrance to about the middle of the block, and the switch GS pertains to this section and is operated by the 15 rod x , which controls the track-semaphore X. The three overhead wires $r' r^2 r^3$ extend from the middle (where the wires $g' g^2 g^3$ end) to the far end of the block, and the switch RS pertains to this section and is operated by the rod 20 y , which controls the track-semaphore Y. The wires $r' r^2 r^3$ are on the prolongation of the wires $g' g^2 g^3$, so that the trolleys T as they leave the one set contact at once with 25 the other set; but, as shown in Fig. 3, the two sets of wires are insulated from and have no electrical connection whatever with one another. Each switch consists of a pivoted lever l and two contact-posts $m n$. The lever 30 l of the switch GS is connected to and moves with the operating-rod x of the caution-signal X, and the lever l of the switch RS is connected to and moves with the operating-rod y of the danger-signal Y. When the signals 35 X Y are at "safety," in which positions they are shown in Fig. 2, then the levers l rest upon the contacts n , and the circuit connections controlled by these switches, respectively, will be through the white or safety lamp W on 40 the locomotive. When, however, either one of the levers $x' y'$ —say the lever x' —is pulled so as to lift its signal X to "caution," the movement of the operating-rod x will cause the switch-lever of GS to swing from contact 45 50 n to contact m , and when this is done the lamp W in the locomotive will be cut out, and the green lamp G will be thrown into circuit and will be excited so long as the trolleys T are on the section-wires $g' g^2 g^3$. Similarly if the rod y be operated to put its signal Y at "danger" the switch-lever l of the switch RS will be shifted from its contact n to its contact m , and in this event the white light W will be cut out and the red light R 55 60 65 in the locomotive-cab will be in circuit so long as the trolleys T are on the section-wires r', r^2 , or r^3 .

The circuit connections are as follows, reference being had to Fig. 5: The battery B (which, if used, may be located in the tower or cabin) is typical of any suitable source of electrical energy. Confining attention to the

green or caution section of the block, the circuit is from one pole of battery to switch GS, where the circuit divides into two branches. 70 The one branch is from contact-post n to the wire g^2 , thence (through the trolley T appropriate to that wire) to the white light W on the locomotive, thence (through the appropriate trolley T) to wire g^3 , and thence back 75 to the other pole of battery. The other branch is from binding-post m to wire g' , thence (through the trolley T appropriate to that wire) to the green light G on the locomotive, thence to wire g^3 , (through the appropriate trolley T,) and thence back to the other pole of battery. Thus as the switch GS is thrown so as to contact with the n or m contact a branch circuit will be completed through one of the two lamps W G on the locomotive to the exclusion of the other. The green-light branch is through the overhead wire g' , the white-light branch is through the overhead wire g^2 , and the overhead wire g^3 is 80 the return-wire common to both branches. 85 Correspondingly in the red or danger section if the locomotive be on that section then the white lamp W or the red lamp R will be in circuit, according to the position of switch RS. If the lever of this switch be on its contact n , 90 then the circuit will be from one pole of battery B (through switch GS and its contact n) to wire r^2 , thence (through its appropriate trolley T) to white light W, thence (through the appropriate trolley T) to wire r^3 , and thence 95 to other pole of battery. If, on the other hand, the switch GS be thrown so as to put its lever on its contact m , then the circuit will be from one pole of battery B (through switch GS and its contact m) to wire r' , thence (through the 100 trolley T appropriate to that wire) to red lamp R, and thence out (through the appropriate trolley T) to wire r^3 and back to other pole of battery. In this instance the white-light branch is through the overhead wire r^2 , the 105 red-light branch is through the wire r' , and the wire r^3 is the return-wire common to both branches. I might use ground or rails for the return, and thus dispense with one of the overhead wires; but this would not be 110 safe in localities where other electrical circuits were used, and I therefore prefer the use of the third wire, so as to secure an all-metal circuit. I may locate in the tower or cabin lights G', W', and R', as seen in Fig. 115 4, duplicates of those employed upon the locomotive and similarly connected up in circuit and controlled from the same levers $x' y'$, so that the operator may be able to assure himself that the circuit connections and 120 conditions are normal. Manifestly if the semaphore or track signals X Y were removed or detached from their operating appliances the rods $x y$ and levers $x' y'$ could be still used to control the circuit connections with 125 the signal-lamps in the locomotive-cab, and thus keep the engineer informed as to the condition of the block. In practice it will be found convenient to place the switches GS 130

RS in the operating cabin or tower. It is immaterial, however, where they are located so long as they have connections whereby they are or may be operated at the time and in the manner hereinbefore stated. Instead of overhead connections these connections can be located at any convenient point alongside of or on the road-bed, and the current itself can be taken from any suitable or convenient source of electrical energy. The circuits of both the caution and danger sections of the block are represented as taken from the same battery; but of course, if desired, each section may have its own battery. Each section, in fact, is in a certain sense a distinct block in itself, although both of them go to make up the larger block and are under one control.

The block system in connection with which I have illustrated my invention is what is known as the "hand" block system—that is to say, a system in which the block-signal is operated by hand; but the invention can be used in connection with the automatic block system also, all that is needed being to connect the switch GS or RS, as the case may be, with the appropriate block-signal or some part moving therewith, so that the two shall move in unison, as hereinbefore explained.

Having now described my invention and the manner in which the same is or may be carried into practical effect, what I claim herein as new, and desire to secure by Letters Patent, is as follows:

1. In an electric block-signal system for railway-trains, a normally open signal-circuit completed through contacts on the locomotive whenever and so long as the latter is on the block, and having branch circuit connections including the one a safety-signal and the other a caution or danger signal, both of which are on the locomotive and in convenient proximity to the engineer, and means controlled from

the tower or cabin appropriate to the block for completing the circuit through either one 45 or said signals to the exclusion of the other.

2. In an electric block-signal system for railway-trains, a normally open signal-circuit completed through contacts on the locomotive whenever and so long as the latter is on the 50 block, and having branches including the one a safety-signal and the other a caution or danger signal, both of which are on the locomotive and in convenient proximity to the engineer, a track-signal or semaphore, an 55 electrical switch and connections between the same and the track-signal whereby the electrical switch shall be thrown to complete the circuit through that branch which includes the safety or the caution or danger signal on 60 the locomotive according as the track-signal is brought to safety or danger substantially as hereinbefore set forth.

3. An electrical block-signal system in which the block is subdivided into caution and 65 danger sections each having a signal-circuit electrically independent of the other, each circuit being normally open and completed through contacts on the locomotive whenever and so long as the latter is on the block-section 70 to which the circuit pertains, and having branches including the one a safety-signal and the other a caution or a danger signal as the case may be, all of said signals being on the locomotive, in combination with means 75 controlled from the tower or cabin appropriate to the block for completing either circuit at will through either one of its branches substantially as and for the purposes hereinbefore set forth.

In testimony whereof I have hereunto set my hand this 13th day of March, 1902.

JAMES T. HAMBAY.
